STAMPING MACHINE

Sol Lifsitz, Detroit, Mich., assignor of one-half
to Israel M. Hertz, Detroit, Mich.

Application December 29, 1934, Serial No. 759,633

11 Claims. (Cl. 101—37)

The present invention pertains to the marking of pieces of laundry, particularly such pieces as are rented by a laundry supply service and pieces owned by hotels and other institutions. At the 5 present time, the marking or stamping of the pieces is done by hand, probably because a mechanical device presents several difficulties. First, a piece of laundry must be re-stamped one or more times before it is discarded, and not all the 10 pieces in a wash require stamping. Again, a timed mechanical marker would require a complicated adjusting mechanism, inasmuch as the pieces handled in different batches, or even in the same batch, at times are not of uniform 15 length.

The principal object of the present invention is to provide a stamping device which is mechanically driven but manually controlled, in order to provide for the irregularities previously 20 mentioned. A second but very important object is to make possible the stamping of the laundry without the expenditure of an appreciable amount of extra time, by causing this operation to be performed during the handling of the work in 25 some other laundering process.

It is well known that the ink adheres to the cloth more firmly if the stamped area is given a heat treatment immediately after the ink is applied. In this connection, still another object 30 of the invention is to furnish this heat treatment.

In order to accomplish these objects, the invention embodies a stamping roller journaled in a suitable bracket carried by the frame work of a conventional laundry machine in which the work 35 is ordinarily subjected to heat, such as a mangle. The roller is mounted close to the conveyor which feeds the machine and is so positioned that parts of its periphery are adapted for tractive engagement with the work carried by the conveyor. 40 Intervening parts of the roller are notched or recessed, and when any one of these parts is disposed immediately over the work, the roller does not turn. The roller assembly carries push pieces within convenient reach of the operator while the 45 latter is feeding a piece of work to the machine. If the piece is to be stamped, the operator pushes the push piece to bring a tractive part of the roller into engagement with the work, whereupon the roller turns and brings the stamp proper 50 into engagement with the work. When the next recessed part of the roller comes to a position immediately over the work, the tractive engagement is broken and the roller stops turning. Thus, the work is stamped only when the operator 55 actuates one of the push pieces.

The invention is fully disclosed by way of example in the following description and in the accompanying drawing in which

Figure 1 is a side elevation of the device;

Figure 2 is a fragmentary plane view thereof, 5 and

Figure 3 is a section on the line 3—3 of Figure 2.

Reference to these views will now be made by use of like characters which are employed to 10 designate corresponding parts throughout.

In Figure 1, the numeral 1 indicates a part of the frame of a conventional laundering machine, preferably one that heats the work passing therethrough, such as a mangle. The support for the 15 stamping device includes two clamp pieces 2 engaging the member 1 and held together by bolts 3. A spring arm 4 is held by the bolts, and one or more shims 5 may be inserted between the arm 4 and the nearer member 2 if necessary or desired. A bearing member 6 has a shank 7 formed with tapped holes 8. These holes are adapted to lie beneath slots 9 in the free end of the member 4, whereby the bearing member 6 may be secured 20 adjustably to the member 4 by means of thumb 25 screws 10 passed through the slots 9 and screwed into the holes 8.

In the arms of the member 6 is journaled a shaft 11 to which is secured a roller 12. Beneath the roller is a flat conveyor 13 which feeds the 30 machine, and this conveyor rides over a table 14 at the roller. It will be seen, however, in Figure 3 that the roller itself does not engage the work 15 passing through the machine. In the periphery of the roller are inserted one or more 35 stamping members 16 arranged parallel to the axis of the roller and spaced from each other. The face 17 of each stamping member is at such a distance from the axis of the roller that it can come into tractive engagement with the piece 40 15, and each face is further formed to impress the work with characters represented by the letters A, B, C, D, E, F, G in Figure 2. It is evident that when one of the spaces 18 between members 16 is disposed immediately over the work, the roller 45 does not turn. The means for bringing a stamping member into engagement with the work, when and as desired, will now be described.

This means consists merely of one or more push pieces, corresponding to the number of 50 members 16 carried by the roller 12, associated with the roller assembly and within convenient reach of the operator while the latter is feeding a piece of work to the machine, so that the roller assembly may be turned to bring one of its tractive 55

parts into engagement with the work. While the push pieces may be carried directly by the roller itself, a preferred construction is illustrated herein. A disk 20 is carried by the shaft 11 at each end of the roller and is the same circumference as the faces 17 of the stamping member 16, in order also to have tractive engagement with the work as may be seen in Figures 1 and 2. However, the periphery of each disk is notched at 5 21 opposite the ends of the spaces 18 between the members 16. The notches 21 are narrower than the spaces 18 and the latter are overlapped by the unmutilated parts 22 of the disk 20 at the trailing side of each space 18, with reference to the 10 direction of rotation indicated by the arrows in Figures 1 and 3, for a purpose which will presently appear. An inking roller 23 is journaled in the bracket 6 and is engaged by the faces 17 as the roller 12 turns on its axis.

15 20 Finger push pieces 24 are fixed to or formed integral with the disks 20 and project outward from the outer faces thereof. These members lie wholly within the projected cylindrical surface embodying the stamping faces 17 or the periphery of the disks 20. The reason for so positioning the push pieces is to maintain them entirely clear of the moving work piece 15 and out of driving engagement therewith or with any other moving part of the machine. They correspond in 25 number to the stamping member 16 carried by the roller 12.

30 20 When a space 18 and its aligned notches 21 lie immediately over the conveyor, just before reaching the position shown in Figure 3, the stamping device is idle and can be brought into tractive engagement with the work only by pushing one of the members 24. These members are so positioned that the lowermost one can conveniently be pushed by the thumb of the operator as he 35 lays a piece of work on the conveyor 13 to be fed to the machine. A slight push brings the leading edge of an unmutilated segment of a disk 20 into engagement with the work, whereupon rotation of the roller is initiated. Because of the previously 40 described relations of the overlapping parts 22 to the spaces 18, the stamp is applied to the work at a pre-determined distance from the entering edge of the work. This distance depends on the spacing between notches 21 which may be established as desired. As the work passes through the 45 laundry machine, it receives a heat treatment which sets the ink of the stamp.

50 20 The operator need use only one hand to start the roller, and only one disk 20 is essential, but the provision of two disks adapts the device for right handed and left handed operators or permits the operator to change hands from time to time. The shaft 11 is in the form of a bolt having a nut 23 at one end so that a roller of a different 55 size or with different stamps may be inserted when desired. Similarly, the inking pad 23 is held by a bolt 26 and nut 27 for interchangeability. The resiliency of the member 4 permits a slight change in the elevation of the stamping 60 device in response to variations in the thickness of the work moving thereunder. Permanent adjustments of elevation are made by use of shims 65 5.

70 20 Although a specific embodiment of the invention has been illustrated and described, it will be understood that various alterations in the details of construction may be made without departing from the scope of the invention, as indicated by the appended claims.

What I claim is:

75 1. In a stamping machine, a shaft, a roller

mounted on said shaft and having a stamping member mounted lengthwise on its periphery and projecting radially outward, said roller being normally freely rotatable on said shaft, a push piece associated with said roller and by means of which the roller can be manually rotated, such push piece lying wholly within the prolongation of the cylindrical surface projected from the facial circumference of said stamping member. 5

2. In a stamping machine, a shaft, a roller mounted on said shaft and having stamping members mounted lengthwise on its periphery and spaced from each other, said roller being normally freely rotatable on said shaft the parts of said roller at the spaces between said members being of smaller radius than the faces of said members, and push pieces associated with said roller and by means of which said roller can be manually rotated, said push pieces lying wholly within the prolongation of the cylindrical surface embodying the faces of said stamping members. 10

3. In a stamping machine, a roller having stamping members mounted lengthwise on its periphery and spaced from each other, the parts of said roller at the spaces between said members being of smaller radius than the faces of said members, a disk carried by said roller at one end thereof and in concentric relation to the roller, said disk having a maximum radius substantially equal to that of said faces, the periphery of said disk having transverse notches opposite the ends of said pieces, and push pieces projecting laterally from one of the faces of said disk, by means of which said disk and roller can be manually rotated, said push pieces lying wholly within the cylindrical surface projected from the maximum circumference of said disk. 25

4. In a stamping machine, a roller having stamping members mounted lengthwise on its periphery and spaced from each other, the parts of said roller at the spaces between said members being of smaller radius than the faces of said members, a disk carried by said roller at each end thereof and in concentric relation to the roller, said disks having a maximum radius substantially equal to that of the faces of said stamping members, the periphery of said disks having transverse notches opposite the ends of said spaces, and push pieces projecting laterally from one of the faces of each disk, by means of which said disk and roller can be manually rotated, said push pieces lying wholly within the cylindrical surface projected from the maximum circumference of said disks. 40

5. In a stamping machine, a roller having stamping members mounted lengthwise on its periphery and spaced from each other, the parts of said roller at the spaces between said members being of smaller radius than the faces of said members, a disk carried by said roller at one end thereof and in concentric relation to the roller, said disk having a maximum radius substantially equal to that of the faces, the periphery of said disk having transverse notches opposite the ends of said spaces, and push pieces projecting laterally from one of the faces of said disk, by means of which said disk and roller can be manually rotated, said spaces being wider than said notches on the trailing side. 55

6. In a stamping machine, a roller having stamping members mounted lengthwise on its periphery and spaced from each other, the parts of said roller at the spaces between said members being of smaller radius than the faces of said members, a disk carried by said roller at one end 70

- thereof and in concentric relation to the roller, said disk having a maximum radius substantially equal to that of the faces, the periphery of said disk having transverse notches opposite the ends 5 of said spaces, and push pieces projecting laterally from one of the faces of said disk, by means of which said disk and roller can be manually rotated, said spaces being wider than said notches on the trailing side, and being disposed immediately 10 behind the trailing edges of said notches.
7. In a machine having a flat conveyor for feeding work thereto, a shaft positioned over said conveyor, a roller journaled on said shaft and being normally freely rotatable, a stamping member 15 mounted lengthwise on the periphery of said roller and projecting radially outward, a push piece associated with said roller and by means of which the roller can be manually rotated, said push piece lying wholly within the prolongation 20 of the cylindrical surface projected from the facial circumference of said stamping member.
8. In a machine having a flat conveyor for feeding work thereto, a shaft positioned over said conveyor, a roller journaled on said shaft and being normally freely rotatable, stamping members 25 mounted lengthwise on said roller and spaced from each other, the faces of said members being of such radius from the axis of the roller as to have tractive engagement with the work carried by said conveyor, the parts of the roller between said members being of substantially smaller radius than said 30 faces, a disk carried by said roller at one end thereof and in concentric relation to the roller, said disk having a maximum radius substantially equal to that of the faces, the periphery of said disk having transverse notches opposite the ends 35 of said spaces, and push pieces projecting laterally from one end of the faces of said disk, by means of which said disk and roller can be manually rotated, said spaces being wider than said notches on the trailing side.
9. In a machine having a flat conveyor for feeding work thereto, a roller journaled over said conveyor, stamping members mounted lengthwise on said roller and spaced from each other, the faces of said members being of such radius from the axis of the roller as to have tractive engagement with the work carried by said conveyor, the parts of the roller between said members being of substantially smaller radius than 40
- 45
- said faces, a disk carried by said roller at one end thereof and in concentric relation to the roller, said disk having a maximum radius substantially equal to that of the faces, the periphery of said disk having transverse notches opposite the ends 5 of said spaces, and push pieces projecting laterally from one of the faces of said disk, by means of which said disk and roller can be manually rotated, said push pieces lying wholly within the cylindrical surface projected from the maximum circumference of said disk.
10. In a machine having a flat conveyor for feeding work thereto, a roller journaled over said conveyor, stamping members mounted lengthwise on said roller and spaced from each other, the faces of said members being of such radius from the axis of the roller as to have tractive engagement with the work carried by said conveyor, the parts of the roller between said members being of substantially smaller radius than said 15 faces, a disk carried by said roller at one end thereof and in concentric relation to the roller, said disk having a maximum radius substantially equal to that of the faces, the periphery of said disk having transverse notches opposite the ends 20 of said spaces, and push pieces projecting laterally from one end of the faces of said disk, by means of which said disk and roller can be manually rotated, said spaces being wider than said notches on the trailing side.
11. In a machine having a flat conveyor for feeding work thereto, a roller journaled over said conveyor, stamping members mounted lengthwise on said roller and spaced from each other, the faces of said members being of such radius from the axis of the roller as to have tractive engagement with the work carried by said conveyor, the parts of the roller between said members being of substantially smaller radius than said faces and push pieces associated with said 30 roller and by means of which said roller can be manually rotated, said push pieces lying wholly within the prolongation of the cylindrical surface embodying the faces of said stamping members.

SOL LIFSITZ.
